UNITED STATES PATENT OFFICE.

DONALD T. ALLEN, OF MILWAUKEE, WISCONSIN, ASSIGNOR TO PRIME MFG. CO., OF MILWAUKEE, WISCONSIN.

PHONOGRAPH.

Application filed August 29, 1925. Serial No. 53,353.

To all whom it may concern:

Be it known that I, DONALD T. ALLEN, a citizen of the United States, and resident of Milwaukee, in the county of Milwaukee and

- 5 State of Wisconsin, have invented certain new and useful Improvements in Phonographs; and I do hereby declare that the following is a full, clear, and exact description thereof.
- 10 This invention relates to phonographs and is in general an improvement over that disclosed in my copending application, No. 129, filed January 2, 1925 for phonographs.

Objects of this invention are to provide a 15 phonograph of the portable type in which a cabinet is provided with a swinging cover, and to so construct the phonograph that it may be played with the cover either open or closed.

20 More specifically, objects of this invention are to provide a portable phonograph which is equipped with an outlet opening for the sound controlled by a slidable flap and to so construct the apparatus that the flap is 25 adapted to slide upwardly and laterally out of the way of the cover and of the records carried by the cover so as to permit closing of the cover even while the phonograph is in operation.

30 Further objects are to provide a very simple construction which may be cheaply manufactured, and which is easy to operate.

An embodiment of the invention is shown in the accompanying drawings, in which:—

35 Figure 1 is a plan view of the phonograph with the cover open, parts of the apparatus being broken away.

Figure 2 is a transverse sectional view on the line 2—2 of Figure 1.

40 Figure 3 is a view corresponding to Figure 2 showing the phonograph in its normal closed position.

Figure 4 is a sectional view on the line 4—4 of Figure 2.

45 Referring to the drawings, it will be seen that the phonograph comprises a cover 1 hinged to the bottom portion 2 adjacent their rear edges. The bottom portion is provided

50 with a top plate 3 spaced a material distance from the bottom plate 4. The front wall 5 of the bottom portion is provided with an outlet aperture 6 for the sound. It is to be noted that the top plate 3 of the body portion

55 of the phonograph is cut away to provide a pocket or channel 7 for a purpose

hereinafter to appear, such channel having a bottom portion 8. In reality the portion 7 constitutes a recess formed in the top plate 3 of the body portion.

It is to be noted particularly from Figures 2 and 3 that a slide 9 is positioned between the front edge of the member 8 and the front wall 5 of the body portion. This slide is normally carried within slots 10 formed at opposite sides of the body portion. Preferably, the slide 9 is provided with a pair of leather tongues 11 which constitute flexible handles to aid in its manipulation.

It is to be noted particularly from Figure 1 that a pair of metal strips 12 are secured to the upper face of the top plate 3 of the body portion. These metal strips are thus spaced a slight distance from the plate 8, as may be seen most clearly from Figure 3. It is to be noted further that the top 1 is provided with a strip 13 (see Figure 3) which, when the device is closed and ready for transporting, contacts with the upper end of the slide 9.

In using the apparatus, the cover is 80 opened and the slide 9 is pulled upwardly by means of the handles 11 until the outwardly projecting trunnions indicated by the reference character 14, which are carried by the slide, are in contact with the lower edge of 85 the metal strips 12. These metal strips may be of angle iron construction, as shown in Figure 4. The slide is tilted and slid backwardly into the space 7, until it occupies the position shown in Figures 1 and 2. It 90 will be seen that in this position the slide is wholly received within the space 7 and constitutes in effect a continuation of the top plate 3. The phonograph may then be adjusted and started and the cover may be 95 closed to eliminate any scratching sounds from the needle in a well known manner.

It will be seen, therefore, that a very simple type of portable phonograph has been provided and is so constructed that the 100 sound delivery opening through the body portion, may be readily closed or uncovered by a movable slide.

It will be seen further that this slide, in either its closed position or its open position, does not interfere with the opening or closing of the cover, but permits the utmost freedom in its manipulation.

When it is considered that the extra records are frequently carried in the cover 1, 110

it is apparent that the invention fulfills a long felt want in providing a slide which does not interfere with the cover in any manner whatsoever.

5 Although the invention has been described in considerable detail, it is to be understood that the invention may be variously embodied and is, therefore, to be limited only as claimed.

10 I claim:

1. A portable phonograph comprising a body portion and a cover, said body portion having a top plate provided with a cutout and having a sound outlet opening in its 15 front wall, and a slide positioned inwardly of said front wall and adapted to be drawn upwardly to uncover said outlet opening, and adapted to be moved rearwardly into the said cutout in the top plate.

20 2. A portable phonograph comprising a body portion and a cover, said body portion having a top plate provided with a cutout and having a sound outlet opening in its front wall, a slide positioned inwardly of 25 said front wall and adapted to be drawn upwardly to uncover said outlet opening and

adapted to be moved rearwardly into the said cutout in the top plate, and means for guiding said slide into said cutout.

3. A portable phonograph comprising a 30 box-like body portion and a cover hinged thereto, said body portion having a top plate terminating short of the front wall of the body portion, a member secured to the under side of said plate and projecting into 35 proximity to said front wall, said front wall having a sound outlet aperture, a slide normally positioned rearwardly of said front wall and closing said aperture and having a pair of outwardly projecting trunnions at 40 its ends adjacent its bottom, and a pair of side strips secured to the top face of said top plate and adapted to guide said trunnions, whereby said slide may be drawn upwardly and slid backwardly above said 45 member, said trunnions being guided between said member and said strips.

In testimony that I claim the foregoing I have hereunto set my hand at Milwaukee, in the county of Milwaukee and State of 50 Wisconsin.

DONALD T. ALLEN.
